We claim the ornamental design for a femoral implant component, as shown and described.

DESCRIPTION

FIG. 1 is a front perspective view from above of the claimed design according to another embodiment;
FIG. 2 is a left side perspective view from above of the claimed design of FIG. 1;
FIG. 3 is a right side perspective view from above of the claimed design of FIG. 1;
FIG. 4 is a front perspective view from below left of the claimed design of FIG. 1;
FIG. 5 is front perspective view from below right of the claimed design of FIG. 1;

(Continued)

FIG. 6 is a top view of the claimed design of FIG. 1; FIG. 7 is a bottom view of the claimed design of FIG. 1; FIG. 8 is a front view of the claimed design of FIG. 1; FIG. 9 is a rear side view of the claimed design of FIG. 1; FIG. 10 is a right side view of the claimed design of FIG. 1; and, FIG. 11 is a left side view of the claimed design of FIG. 1. The ornamental design which is claimed is shown in solid lines in the drawings. The broken lines in the drawings are for illustrative purposes only and form no part of the claimed design.

While the accompanying drawings illustrate one or more exemplary embodiments, it should be understood that according to other exemplary embodiments that should be considered to be within the possession of the inventors of the present application at the time this application is being filed, it is contemplated that any illustrated solid lines (or portions thereof) may be converted to broken lines and that any illustrated broken lines (or portions thereof) may be converted to solid lines so as to claim or disclaim portions, components, or sub-components of the designs shown. It is further contemplated that shading may be added or removed to claim or disclaim the corresponding surfaces.
